METERING DEVICE FOR WEFT IN LOOMS

Alexander C. Krukonis, deceased, late of Auburn, Mass., by Myrtle Krukonis, administrator, Auburn, Mass., and Edwin F. Dolbear, Worcester, Mass., assignors to Crompton & Knowles Corporation, Worcester, Mass.

Filed Sept. 20, 1963, Ser. No. 311,285

2 Claims. (Cl. 139—124)

This invention relates to improvements in weft to looms operating with an outside stationary weft package, and more particularly to needle looms of the type set forth in Patent No. 2,625,959 which weaves a narrow "tape" fabric.

In the type of loom just described, a weft laying needle draws filling from a source outside the loom, such as a weft package. As the needle reciprocates it draws weft from the package intermittently. This action jerks the filling and tends to draw off more filling than is needed, causing an unevenness in the width of the fabric. Attempts to solve the problem have resulted in using various tension devices including a spring tension which is placed between the weft laying needle and the package. The spring yields from normal position at the time of greatest demand and then returns to normal position to take up the slack of any excess weft that has been drawn off. Even this improvement has not completely solved the problem of unevenness in the fabric. Due to the variable momentum of the filling, more or less of it will be drawn off than is needed as the needle makes its insertion. As a result the spring tension devices take up varying amounts of slack, thus producing variations in the weft tension, and hence also in the width of the fabric.

Another condition found in the type of loom mentioned is the so-called "ballooning" over the supply package which is also caused from the jerking of the filling as it is being pulled from the package. This ballooning upsets the normal twist in the filling either by untwisting it or twisting it further, the latter causing an unwanted crimp.

The foregoing tension and ballooning defects found in previous looms have been eliminated by the structure set forth herein by the addition of a positive feed roll which is placed between the weft package and the spring tension means. Because the amount of filling that is fed from the feed rolls to the spring tension means is fixed, the spring tension always has the same amount of slack to take up, resulting in an even tension which produces cloth of uniform width.

It is a further object of the invention to provide a conical feed roll which is adjustable to feed different amounts of weft.

Another object of the invention is to provide means and method for adjusting the feed roll while the loom is running, one result of this condition being the possibility of effecting slight variations in the width of the fabric without stopping the loom.

These and other objects will appear from the following description in connection with the accompanying drawings, which show two forms of the invention, and wherein

FIGURE 1 is a fragmentary plan view of a double fabric needle loom with the preferred form of the invention attached thereto,

FIGURE 2 is a side elevation looking in the direction of arrow 2, FIGURE 1,

FIGURE 3 is a front elevation looking in the direction of arrow 3, FIGURE 1,

FIGURE 4 is a view similar to FIGURE 3 showing a modified form of the invention, and

FIGURE 5 is a side elevation of the modified form of the invention looking in the direction of arrow 5, FIGURE 4.

2

Referring to FIGURES 1 and 2 and the preferred form of the invention, there is shown a table top 1 of a loom L which supports a bearing stand 2 with right and left-hand bearing members 4 and 6 which have a shaft 8 rotatable therein. Shaft 8 extends through bearing members 4 and 6 and has affixed to its outer ends conical weft feeding rolls 10-10' by set screws 12-12'.

Table 1 also supports right and left-hand harness frame guides 14 and 16 respectively between which harness frames 18 are reciprocated. Also supported on table top 1 is a reed or beat-up member 20; also right and left-hand inserting needles 22 and 24 supported by needle holding arms 26 and 28 respectively which, through right and left-hand crank mechanisms 29 and 30, operate said weft inserting needles to reciprocate through successive sheds in the warp W. Threaded through eyes 32 in needles 22 and 24 are right and left-hand filling threads F and F' which are to be incorporated into right and left-hand fabrics 34 and 36.

Referring more particularly to FIGURE 1, the loom L has a main drive shaft 38 on which there is connected mechanism not shown to operate needles 22 and 24. Attached to the end of shaft 38 is a pulley 40 which drives another pulley 42 through a timing belt 44. Pulley 42 is fixed to rotate with reed shaft 46 which drives reed 20 in timed relation with the reciprocating needles 22 and 24. Also fixed to shaft 46 is a pulley 48 which drives a pulley 49 through another timing belt 50. Pulley 49 is fixed to and rotates with shaft 8 which rotates weft feeding rolls 10 and 10' in timed relation with reed 20 and weft inserting needles 22 and 24.

The loom shown in FIGURE 1 is for weaving two individual pieces of fabric and the mechanism for feeding weft for one fabric is the same as for the other and it is deemed sufficient to describe the mechanism on the right-hand side only of the loom for weaving fabric 34. Located on the outside of the loom L is a weft package 52 from which filling is drawn through a tension means 53, through a guide 54, and is given one wrap around feed roll 10, through another guide 55, then forward and upward through a pair of guides 56 and 57 between which the filling passes through the eye 58 of a spring tension 59. After passing through guide 57 the filling passes through eye 32 of needle 22 and then to the cloth 34.

Referring to FIGURES 2 and 3, there is mounted on bearing member 4 a bracket 60 held in place on member 4 by bolts 61. Extension 62 of bracket 60 supports a block 63 which has a foot 63' slidable along a flat surface 65 on the bracket 60, and has threaded through it a screw 64 which extends to an upwardly extending part 66 of bracket 60 which it is rotatably held and prevented from moving to the right or left as shown in FIGURE 3. Secured to the right-hand end of screw 64 by a set screw 66 is a knurled adjusting wheel or thumb grip 67. Rotation of wheel 67 causes block 63 to move to the left or right along rod 64, depending on the direction of turning of screw 64. Block 63 has affixed thereto a guide positioner plate 70 which almost encompasses feed roll 10. The upper end of plate 70 has two spaced slots 71 and 72 through which passes the filling F prior to and then after being wrapped around roll 10 and which act to position the filling F along the length of feed roll 10. Slots 71 and 72 are formed deep enough into plate 70 so as to be lower than the smaller end of cone 10. Plate 70 has right and left-hand extensions, as viewed in FIGURE 2, which support guides 54 and 55.

As feed roll 10 rotates at a fixed speed in relation to the rest of the loom, a fixed amount of weft, dependent on the part of roll 10 engaged by the weft, will be drawn from package 52. In going from the package 52 to the feed roll 10 the filling passes through tension device 53,

mounted on a package container 74, which provides just enough tension to keep the filling taut around the feed roll 10. Feed roll 10 pays off the filling at the same rate as it draws from the package 52, and as the filling comes off roll 10 it passes through guide 55 and then through guides 56, 57, eye 58 and to needle 22 as previously described. When needle 22 moves back to its furthest outside position it is not using filling as fast as the feed roll 10 is paying it off, thus producing a slack which is taken up by the spring 59. Upon insertion of needle 22 into the shed, weft is used at a faster rate than is being payed off by roll 10 and this extra weft is taken from the slack previously taken up by spring 59. The amount of weft being fed from the roll 10 is fixed so that spring 59 always has the same amount of slack to take up. This results in an even tension at a particular point in the cycle from one pick to another, producing a uniform width of cloth.

If it is desired to vary the width of cloth, weft feed can be adjusted by turning wheel 67 which acts to move block 63 to the right or left as viewed in FIGURE 3, which positions guide plate 70 along roll 10 so that the filling is wrapped around a portion of the roll having a different circumference. Plate 70 is so shaped as to almost enclose roll 10, forming a circular opening 76 which is large enough for the largest part of feed roll 10 to pass through.

Referring to FIGURES 4 and 5, there is shown a modified form of feed roll and also a modified form of guide and adjusting means. Attached to shaft 8 by set screw 80 is a conical feed roll 82 with a series of annular grooves 84.

During operation of feed roll 82 filling is drawn from weft package 52 through tension 53 as in the preferred form of the invention. From the tension means 53 the filling passes through a guide 86, is given one wrap around one of the grooves 84, and then is passed through guide 87 and then up to guide 56 after which the operation is the same as that described for the preferred form of the invention.

Bolted at 88 to bearing member 4 is a bracket 89 which is bent so that it has a portion 90 which extends from bearing member 4 at the same angle as does the top element of feed roll 82. Portion 90 of bracket 89 has a guide supporting block 92 slidable thereon which can be affixed thereto in adjusted position by a thumb screw 94. Block 92 supports guides 86 and 87 which align the weft around one of the grooves 84.

To adjust for the amount of weft feed from roll 82, thumbscrew 94 is loosened so that block 92 is free to slide along extension 90 of bracket 89. Moving block 92 along extension 90 aligns guides 86 and 87 along a different groove causing the filling to be moved over to the new position.

Having now particularly described and ascertained the nature of the invention and in what manner the same is to be performed, what is claimed is:

1. In a loom operating with a weft package from which weft is fed to the loom to be incorporated into a fabric by weft laying means,

(a) weft feeding means between said package and said weft laying means including a generally conical surface having the weft trained therearound and rotatable to feed a selected amount of weft to said weft laying means,

(b) weft tensioning means between the weft feeding means and the weft laying means to receive said amount of weft and to maintain a constant tension on the weft during feeding thereof to said weft laying means,

- (c) a second weft tensioning means between said weft feeding means and said package to maintain tension on the weft leading to said feeding means,
- (d) drive means for said weft feeding means operating to rotate the latter at a constant rate of speed to effect feeding of selected amount of weft,
- (e) guide means to maintain the weft in position on said weft feeding means,
- (f) adjustable means including a screw parallel to the axis of the conical surface and means connected to said guide means screw threaded on said screw effective upon turning of the latter to cause the guide means to move parallel to said axis of the conical surface, said movement causing the weft to move along the weft feeding means during loom operation to vary the rate of feed of weft to the loom to vary the width of the fabric,
- (g) said loom having a flat surface parallel to said screw, and said adjustable means connected to the guide means has a foot engaging the flat surface on each side of a right angle projection of the axis of the screw on said flat surface.

2. In a loom operating with a weft package from which weft is fed to the loom to be incorporated into a fabric by weft laying means,

(a) weft feeding means between said package and said weft laying means including a generally conical surface having the weft trained therearound and rotatable to feed a selected amount of weft to said weft laying means,

(b) weft tensioning means between the weft feeding means and the weft laying means to receive said amount of weft and to maintain a constant tension on the weft during feeding thereof to said weft laying means,

(c) a second weft tensioning means between said weft feeding means and said package to maintain tension on the weft leading to said feeding means,

(d) drive means for said weft feeding means operating to rotate the latter at a constant rate of speed to effect feeding of said selected amount of weft,

(e) guide means having slotted members on each side of the feeding means, said slots being of sufficient depth to accommodate the wefts whether it engages the largest or smallest diameter of the conical surface to maintain the weft in position on said weft feeding means,

(f) adjustable means including a screw parallel to the axis of the conical surface and means connected to said guide means screw threaded on said screw effective upon turning of the latter to cause the guide means to move parallel to said axis of the conical surface, said movement causing the weft to move along the weft feeding means during loom operation to vary the rate of feed of weft to the loom to vary the width of the fabric.
